E. G. BURNS

SURGICAL PROTECTIVE GUARD OR SHIELD

Filed August 6, 1925

UNITED STATES PATENT OFFICE.

ERNEST G. BURNS, OF ATLANTA, GEORGIA, ASSIGNOR OF ONE-HALF TO SAMUEL J. SINKOE, OF ATLANTA, GEORGIA.

SURGICAL PROTECTIVE GUARD OR SHIELD.

Application filed August 6, 1925. Serial No. 48,572.

This invention relates to surgical guards or shields and the primary object of the same is to provide a comparatively simple and effective means for protecting the eyes and other portions of the body of a physician or other user of a syringe against infectious germs while treating cases of gonorrhea or the like with irrigating fluids.

Specifically, the main purpose and advantage of the improved guard or shield is to protect the eyes of a physician against gonorrhreal conjunctivitis by so constructing the shield and applying the same to a syringe tube and nozzle, as to prevent not only the irrigating fluid but also the urethral pus from entering the eyes of the operator during the process of urethral irrigation. It often happens that, with the type of shield generally used, the end of the nozzle becomes impinged upon the urethral membrane, with the result that the face and eyes are not protected and the irrigating fluid carrying the poisonous matter strikes or is thrown into the face and eyes of the operator. By using the present improved protective shield, which has transparent means constituting the main covering body or extension thereof through which the operator may view the application of the syringe nozzle to the affected part, the danger just specified is entirely eliminated. Since gonorrhea of the eyes is a condition with a bad prognosis, the affection of eye or eyes generally terminates in destruction and loss of sight, so that the advantage of the present improved guard or shield is obvious. Moreover, the improved guard or shield prevents the clothes of the patient and physician from becoming soiled or contaminated.

The improved guard or shield can be used in the treatment of any condition of the genito-urinary tract where it is necessary to give irrigations, for instance, in acute catarrhal urethritis, chronic catarrhal urethritis, bladder irrigations, and in other similar treatments, and furthermore, the improved guard or shield may be practically used in administering vaginal irrigations for other physical affections that require irrigating treatments.

In the accompanying drawing a preferred form of the improved guard or shield is shown and is subject to modifications in the details of construction, proportions and gen-

eral dimensions within the scope of the invention.

In the drawing:

Fig. 1 is a side elevation of the improved guard or shield, showing the irrigating tube broken away in part.

Fig. 2 is a detail elevation of the upper portion of the improved guard or shield shown in a plane at right angles to that illustrated in Fig. 1.

Fig. 3 is a horizontal section on an enlarged scale on the line 3—3, Fig. 1, showing the irrigating tube fully open.

Fig. 4 is a view similar to Fig. 3, showing the irrigating tube closed or shut off by clamping means engaging the same.

Fig. 5 is a detail elevation of a part of the tubular stem and irrigating tube controlling means, showing the closing means for the tube in compressed condition.

Fig. 6 is a top plan view of the improved guard or shield.

The improved device comprises essentially a guard or shield generally designated by the numeral 5, a tubular stem 6, preferably of metal, a yieldable or collapsible tube 7 interposed in said stem, a compression bulb 8 attached to the end of the tube 7, oppositely disposed spring clamps or valve members 9, and a nozzle 10 mounted and held in the central portion of the guard or shield member 5 and connected to the yieldable or collapsible tube 7. The guard or shield member 5 comprises a base bowl or body 11, preferably of the form shown, and having a collar 12, the nozzle 10 extending through the center of this base bowl and secured at one end to the one end of the tube 7 as shown by dotted lines in Fig. 1. Projecting from the base bowl 11 is an extension 13, consisting of an open frame comprising longitudinal bars 14 and 15 and a suitably curved rim 16 at the terminal of the extension. The bars 15 form the terminating devices for the extension, which extends only partially around the base bowl 11, there being a clear open space between the bars 15. Fitted against the inner side of the bars 14 and 15 and the rim 16 is a transparent covering 17 of mica, celluloid or any other suitable material, the said covering having its side edges removably fitted in inner grooves 18, formed in the terminating bars 15, as clearly shown

85

100
105

by Fig. 6, the outer edge of the covering 17 having substantially the same contour as the rim 16. When the covering 17 is applied to the extension 13 of which it forms a part, the outer and inner extremities of the said cover closely fit respectively against the inner side of the rim 16 and the base of the said extension in a suitable groove or seat therefor, as indicated in dotted lines 10 at 19, Fig. 1, and in full lines in Fig. 2. The covering 17 has such close engagement with the parts of the extension 13, as above explained, as to prevent all possibility of leakage of the irrigating fluid which the improved device as a whole is adapted to apply to an affected physical part. The extension 13 extends outwardly beyond the reduced injecting terminal 20 of the nozzle 10, and this nozzle may be of any preferred 20 shape or general dimensions and material adapted for the purpose. By leaving the guard or shield member 5 open, it is obvious that it can be applied to the patient with convenience, and in the application 25 thereof the extension is disposed between the part under treatment and the operator, to thereby shield the face and eyes as well as the body of the operator from a splash or out-throw of the irrigating fluid during 30 the treatment.

The tubular stem 6 is also made of non-corrodible material, either metal or a composition of materials, and is secured at its outer end to the collar 12, the yieldable or collapsible tube 7 extending through the said stem. Adjacent to the collar 12 the stem 6 at diametrically opposite points is formed with openings 21, which have curved walls 22 to expose sufficient opposite 40 portions of the tube 7 to permit engagement therewith of the clamping or valve means 9. The clamping or valve means 9 are preferably formed from the material of the stem 6 and comprise normally outwardly 45 bowed shanks 23, which at their outer terminals are diverged and provided with angular inwardly projecting gripping heads 24 with inner blunt edges 25 to engage diametrically opposite portions of the tube 7. 50 The clamping and release operations of the members 9 are controlled by a tubular slide 26 mounted on the stem 6 and having a gripping flange 27 surrounding the same, whereby the said slide may be easily manipulated or pushed in one direction to force the stems 23 and clamping heads 24 of the members 9 inwardly against the tube 7, or be pushed in the opposite direction to release the heads 24 from compressing engagement with the tube 7. The stem 6 also has a finger ring 28 secured thereto for convenience in positively holding the improved device in its applied position and prevent any tendency of the guard or shield member 5, including the bowl 11 and extension 13, to

be displaced. The tubular stem 6 also permits the operator to firmly grasp the same without in the least affecting the tube 7, and the finger ring 8 further functions in permitting the stem to be positively held while 70 moving or shifting the slide 26 with its flange 27. The tube 7 may be as long as desired and the free end thereof beyond the bulb 8 may be connected to or associated with a source of supply of irrigating fluid. 75

The operation of the improved device is very simple. Assuming that the free end of the tube 7 beyond the bulb 8 has been properly associated with the source of supply of the irrigating fluid desired to be 80 injected into the patient, the physician or operator then applies the shield member with its extension over the affected part with the extension 13 between the part under treatment and himself and the nozzle 85 20 is more or less inserted in the organ to be treated. After the device has been thus applied the bulb is alternately compressed and released, to forcefully expel the irrigating fluid through the nozzle, with safety 90 to the physician or operator, in view of the fact that any splash that may occur will be held within the extension 13 and bowl 11, and thus protect the physician or operator against injury to the face or eyes or soiling 95 of the clothing. The improved surgical guard or shield also protects the body as well as the clothing of the patient treated. The flow of the irrigating fluid through the tube 7 may be quickly shut off by compressing 100 the clamping or valve members 9 through the actuation of the slide 26, the heads 24 of the said clamping or valve members 9 then assuming the position shown by Fig. 4. Subsequently the said clamp or 105 valve members 9 may be released to permit the irrigating operation or full flow of the fluid through the tube, or permit the tube to assume its normal distended position as shown by Fig. 3. It will be seen that the 110 openings 21 are large enough to permit unimpeded or free operation of the heads 24 in effecting a complete construction of the portion of the tube exposed by said 115 openings.

The improved surgical guard or shield, in addition to possessing the advantages heretofore specified, may also be easily cleaned and asepticized, and as hereinbefore indicated, the eyes and other portions of the body of a physician or operator are fully protected against infectious germs, particularly while treating cases of gonorrhœa and the like with irrigating fluid. The extension 13 serves as a hood under which the work is accomplished, and the bowl or cup-like base 11 adds materially to the efficiency of the improved device. 125

The use of the bulb 8 is not essential in the operation of the improved protective 130

guard or shield, since it is obvious that any holding means having a gravitating action may be used for producing the requisite flow or supply of the fluid medicament. Furthermore, such materials may be used in the formation of the tube 7 as to render the latter non-corrodible and not affected by the various chemicals carried in the fluid that may pass therethrough. In other words, it is proposed to use any suitable means for supplying the medicated fluid to the guard or shield.

What is claimed as new is:

1. In a surgical guard or shield, a shield member comprising a bowl with an extension partially therearound comprising an open frame with a transparent covering, a tubular means attached to the bowl, a nozzle extending upwardly into the latter, and a tubular means connected to the nozzle for dispensation of irrigating fluids.

2. In a surgical guard or shield, a bowl having an open framework extension partially around the same, a transparent covering for the extension, a nozzle held in the center of the bowl and shielded by the said extension and covering, irrigating tubular means attached to the nozzle, and means for controlling the flow of fluid through the said tubular means.

3. A surgical guard or shield of the class specified, having a bowl with an open framework extension partially therearound, a transparent covering for the said extension, a nozzle held by the bowl and shielded by the said extension and covering, flexible tubular irrigating means attached to the nozzle, and means for engaging opposite portions of the flexible tubular means for controlling the flow of irrigating fluids through the latter.

4. A surgical guard or shield of the class specified comprising a tubular stem, a flexible tubular means extending through the stem and having one end adapted for connection to a pressure device, a bowl secured on the end of the stem and having an open framework extension having a transparent covering, the extension and covering extending partially therearound, a nozzle held within the bowl and shielded by the said extension and to which the other end of said

tubular means is connected, opposite portions of the flexible tubular means being exposed through the stem, and means associated with the stem for engaging diametrically opposite portions of the tubular means to close and release the latter and control the flow of irrigating fluids therethrough.

5. A surgical guard or shield of the class specified comprising a tubular stem with opposed openings in a portion thereof and spring valves having heads disposed opposite said openings, a flexible tube extending through the stem and having one end adapted for connection to a pressure means, a slide device operable to compress and release the said spring valves for cutting off free flow of an irrigating fluid through the said flexible tube, a bowl-like member secured to the end of the stem and provided with an open framework extension having a transparent covering, the extension and covering extending partially around the bowl, and a nozzle secured to the bowl and the other end of said flexible tube and shielded by the open framework extension and transparent covering, the transparent covering being detachable and replaceable by another similar device, and means carried by the stem to assist in holding the latter during application and operation thereof.

6. In a device of the class specified, a bowl having an open framework extension partially therearound provided with a transparent covering, a nozzle held within the center of the bowl at a distance from the extension and shielded by the latter, and means connected to the nozzle for supplying the same with an irrigating fluid.

7. In a device of the class specified, a bowl having an open framework extension partially therearound provided with a transparent covering, a nozzle held within the center of the bowl at a distance from the extension and shielded by the latter, and means connected to the nozzle for supplying the same with an irrigating fluid, the transparent covering being removable and adapted to have a similar device substituted therefor in the event of fracture.

In testimony whereof I have hereunto set my hand.

ERNEST G. BURNS.
